Primary Examiner — Deanna L Fluegeman

(57) CLAIM

The ornamental design of a display screen with graphical user interface, as shown and described herein.

DESCRIPTION

The FIGURE is a front view showing an embodiment of my new display screen with graphical user interface. The broken line showings of the display screen, pictures, patterns, characters, and symbols are for illustrative purposes only and form no part of the claimed design.

1 Claim, 1 Drawing Sheet
